1 Claim

ABSTRACT OF THE DISCLOSURE

A flat dish has suction cups on the periphery, a decoration in the center and a steep groove at the bottom. Tips of spoons fit in the grooves and the spoons are then held in the vertical position forming an artistic pattern. This invention relates to a spoon-holder which can hold spoons in an upright position and makes them look very pretty when displayed for sale or placed on a table and more particularly to a spoon-holder which can so hold the spoons that colors will be reflected from the surfaces of the spoons.

DESCRIPTION OF THE DRAWINGS

FIGURE 1 shows a plan of a spoon-holder according to the present utility model.

FIGURE 2 shows a partial longitudinal sectional view of said spoon-holder; and

FIGURE 3 shows an oblique view illustrating the use 30 of said spoon-holder.

SUMMARY OF THE INVENTION

The spoon-holder of this contrivance has a flat dish 1, the periphery of the inside of said dish being provided

2

with several suction cups 2; colored pieces 3 of flower and other patterns being planted at the center of said dish; and the bottom plate 4 of said dish being provided with a stepped groove 6, into which the tips of spoons 5 are positioned with their bowls arranged around the planted colored pieces 3.

Such being the composition of this contrivance, when the spoons 5 are sucked in upright position by the suction cups 2 as shown in FIG. 3, the plated surfaces of bowls reflect the colored pieces 3 and the whole thing looks very beautiful. Moreover, since the spoon tips engage the stepped groove 6 formed at the bottom plate 4 of the holder, a perfect upright position can be maintained, making the display on the table look pretty and vastly enhancing its value.

What is claimed is:

1. A spoon holder comprising a dish 1 with a bottom plate 4; the periphery of the inside of the dish being provided with a plurality of suction cups 2 for holding the spoons in an upright position; means at the center of the dish for holding colored pieces of flowers 3 and other patterns; said bottom plate having a stepped groove 6 into which the tips of spoons 5 fit whereby the spoons are positioned so that their bowls are arranged around the colored pieces 3.
